UNITED STATES PATENT OFFICE.

BION S. BENNER, OF MANKATO, AND ERNEST L. BENNER, OF BEMIDJI, MINNESOTA.

AUTOMOBILE-LIFT.

1,218,510.

Specification of Letters Patent.

Patented Mar. 6, 1917.

Application filed November 2, 1915. Serial No. 59,243.

To all whom it may concern:

Be it known that we, BION S. BENNER and ERNEST L. BENNER, citizens of the United States, residing, respectively, at Mankato and Bemidji, in the counties of Blue Earth and Beltrami, State of Minnesota, have invented new and useful Improvements in Automobile-Lifts, of which the following is a specification.

- 10 This invention is an improved machine for automatically lifting an automobile clear from the floor and thus relieve the tires from stress when the machine is in the garage or is otherwise out of use and which also keeps 15 the wheels out of oil or grease that may be on the floor and greatly facilitates repairs and changes on tires or the like and also greatly facilitates the washing of the automobile.
- 20 The object of the invention is to provide an improved machine of this character which is simple in construction, which operates automatically and which not only lifts the car, when the car is moved in one direction, but 25 also automatically lowers the car when the same is moved in the reverse direction.

The invention consists in the construction, combination and arrangement of devices hereinafter described and claimed.

- 30 In the accompanying drawings:—

Figure 1 is a side elevation of an automatically operating automobile lift constructed in accordance with our invention, showing the same in use with the wheels 35 lifted and with the friction plates applied to the rear wheels.

Fig. 2 is a longitudinal sectional view of the same.

Fig. 3 is a plan of the same.

- 40 Fig. 4 is a transverse sectional view of the same.

In the embodiment of our invention we provide a base frame 1 which in practice may be made of angle iron or other suitable 45 material and which is here shown as comprising a pair of side bars 2, front and rear cross bars 3—4 and intermediate cross bars 5—6. A pair of standards 7 are mounted on the bars 2 at a point substantially mid- 50 way between the front and rear ends of the base frame and near the rear ends of said bars are a pair of uprights 8, each of which has a series of adjusting openings 9 arranged vertically. The ends of the cross 55 bar 5 project beyond the sides of the base frame and a pair of friction plates 10 which

are parallel with the base frame are secured at their rear ends to the projecting ends of the cross bar 5 and their front ends are free to move vertically being arranged near the front end and at opposite sides of the base frame.

A rocker frame 11 is mounted at a point somewhat in front of its center on a pivoting rod 12, which rod is pivotally mounted in 65 bearings 13 on the upper ends of the standards 7. The rocker frame provides a pair of longitudinally arranged side channel bars 13', a rear cross bar 14 which connects said channel bars and a cross bar 15 which also 70 connects said channel bars at a suitable distance from their front ends. Each channel bar has a depression 16 in the bottom of its channel at a suitable distance from its front end. The rocker frame is mounted for piv- 75 otal movement about a horizontal axis so that when its front end is raised its rear end is lowered, and vice versa as will be understood. A pair of travelers 17 are mounted for longitudinal movement in the channel 80 bars and each of said travelers has a horn 18 near its rear end and is adapted to rest with the front end in the depression of one of the channel bars. Each traveler also has a slight elevation 18^a at its front end to engage the rear side of the front axle when the automobile is backed off the lift and cause the traveler to be returned to its initial 85 position in one of the depressions 16.

A crank shaft 19 is mounted in bearings 90 20 on the bars 2 near their front ends and is provided with a pair of crank arms 21 each of which is connected as at 22 to the front end of one of the friction plates 10 and is also connected by a pitman 23 to the 95 front portion of one of the channel bars of the rocker frame. At the rear end of the base frame are a pair of bumpers 24 for engagement with the front wheels of an automobile when mounted on the rocker frame, 100 the said bumpers being mounted for vertical and longitudinal adjustment and being secured at any desired adjustment by bolts 25 which are inserted in appropriately arranged openings 9 of the uprights 8. A rod 105 26 is arranged for longitudinal movement in a guide yoke 27 which is attached to the lifting shaft or bar 12 and in a stanchion 28 which rises from the rear intermediate cross bar 6. A prop arm 29 has its lower 110 end pivotally mounted as at 30 on the rear cross bar 4 and is provided at suitable dis-

tances from its upper end with stop shoulders 31—32. A spring 33 moves the rod 26 normally forwardly with the prop arm and a trip arm 34 extends upwardly from said 5 rod and is arranged for adjustment at any suitable point. Normally the rocker frame is arranged with its front end lowered and its rear end raised and with its rear cross bar engaged with the stop shoulder 31 of 10 the prop arm. When an automobile is moved longitudinally over the lift, from the front end of the latter the axles engage with the travelers and the front wheels are gradually raised as will be understood. When 15 the front axle engages the trip arm 34, said trip arm moves the rod 26 rearwardly against the tension of the spring 33 thus causing the prop arm to be correspondingly moved so that the stop shoulder 31 thereof 20 disengages the front cross bar of the rocker frame and owing to the location of the pivot axis of the rocker frame somewhat to the front of its longitudinal center the rocker frame tilts, its rear end being lowered and engaged with the stop shoulder 32 25 and its front end being raised so that it comes in contact with the rear axle of the automobile, the rear wheels also of the automobile are lifted from the ground and as 30 the front wheels engage the bumpers the rear wheels are engaged at the under sides of their tires by the friction plates 10 the pitmen 23 and the cranks of the crank shaft raising the rear ends of said friction plates 35 as will be understood.

In practice the main or base frame is preferably provided with casters under its rear corners and a cone shaped pivot is preferably provided under the center of its front 40 cross bar to anchor the machine and allow it to adjust itself in the event that the automobile should not be run on exactly straight. Preferably also the front ends of the bars 2 are inturned, as shown to prevent the wheels 45 from climbing them. The pitmen 23 are longitudinally adjustable and are here shown as each comprising a pair of members slidably related, provided with adjusting openings and secured together at any 50 desired adjustment by means of a bolt and said adjusting openings.

Having thus described our invention, we claim:—

1. An automobile lift comprising a pivotally mounted rocker frame on which an 55 automobile is adapted to be run, a prop to normally hold the rear end of the rocker frame in elevated position, a trip to disen-

gage the prop and friction elements operated by the rocker frame to normally engage under the rear wheels of the automobile when they are raised by the tilting of the rocker frame.

2. An automobile lift of the class described comprising a base frame, a rocker frame mounted thereon for longitudinal movement in a vertical plane, a support for the rear end of the rocker frame with the latter when raised, tripping means for disengaging the support for the rocker frame and arranged for operation by an automobile run over the frame, friction elements for application to the under sides of the automobile wheels, cranks on the base frame and connected to said friction elements, and pitmen connecting the cranks to the front end of the rocker frame.

3. An automobile lift comprising a pivotally mounted rocker frame on which an automobile is adapted to be run, a prop to normally hold the rear end of the rear frame in elevated position, a trip to disengage the prop, and means operated by the rocker frame to normally engage under the rear wheels of the automobile, when they are raised by the tilting of the rocker frame.

4. An automobile lift comprising a pivotally mounted rocker frame on which an automobile is adapted to be run, travelers arranged for longitudinal movement on said 90 rocker frame and arranged for engagement by the front automobile axle, a prop to normally hold the rear end of the rocker frame in elevated position, a trip to disengage the prop, and means operated by the rocker 95 frame to normally engage under the rear wheels of the automobile when they are raised by the tilting of the rocker frame.

5. An automobile lift comprising a pivotally mounted rocker frame on which an 100 automobile is adapted to be run, a prop, spring actuated means to cause the prop to normally hold the rear end of the rocker frame in elevated position, a trip to disengage the prop, and means operated by the 105 rocker frame to normally engage under the rear wheels of the automobile when they are raised by the tilting of the rocker frame.

In testimony whereof we affix our signatures in presence of two witnesses.
